CLAIM

The ornamental design for a necklace as shown and described.

DESCRIPTION

1. Necklace

1.1 : Perspective

1.2 : Front

1.3 : Back

1.4 : Top

1.5 : Bottom

1.6 : Right

1.7 : Left

1.8 : Enlarged view of the portion A-A

The characteristic features of the design reside in the shapes as shown in the reproductions; The broken lines in the reproductions form no part of the claimed design; The letter A and arrows in the reproductions are for the purpose of depicting the enlarged portions and form no part of the design; The dot-dash lines shown in the reproductions indicate the indeterminate length of the designs; The reproduction 1.8 is the enlarged view of the portion A-A in the reproduction 1.2.
